UNITED STATES PATENT OFFICE.

CHARLES H. ANDERSON, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

DRAWER-STOP.

1,214,495.

Specification of Letters Patent.

Patented Feb. 6, 1917.

Application filed December 1, 1915. Serial No. 64,561.

To all whom it may concern:

Be it known that I, CHARLES H. ANDERSON, a citizen of the United States of America, residing at Grand Rapids, in the county of Kent and State of Michigan, have invented certain new and useful Improvements in Drawer-Stops; and I do hereby declare the following to be a full, clear, and exact description of the invention, such as

10 will enable others skilled in the art to which it appertains to make and use the same.

This invention relates to a drawer stop and it is the object and purpose thereof to provide a stop which may be interposed in 15 the path of movement of the drawer as it is entered into a casing or compartment and stop it so that the front of the drawer will not engage against the front edges of the partitions or the like which bound the

20 drawer receiving opening.

Heretofore it has been usual to attach blocks to partitions or sides of a drawer receiving opening to serve as stops but it has been found that after the drawer has been inserted a few times and struck against said blocks, the blocks break away or are otherwise injured so as to be practically useless as drawer stops, and thereafter the stoppage of the drawer is made by engagement of the 25 front of the drawer against the front edges of the sides or partitions bounding the drawer opening. After a short time the front becomes broken from the drawer practically destroying it.

30 My invention consists in the provision of a stop formed of metal, preferably, which may be applied and interposed in the path of movement of the drawer and which may be struck an indefinite number of times by the drawer without injury or any likelihood of the stop becoming disarranged. The construction by which these ends are attained together with others which have not been 35 specifically enumerated but which will appear as the description progresses is shown in the accompanying drawings, in which:

Figure 1 is a plan view of a case or compartment in which a plurality of drawers are located, the top of the case or compartment being removed. Fig. 2 is an enlarged 40 partial sectional and side view of the rear end of a drawer compartment showing the

drawer stop in position. Fig. 3 is a section taken on the line 3-3 of Fig. 2 looking downward upon the drawer stop; and Fig. 4 55 is a perspective view of one element of the drawer stop apparatus.

Like reference characters refer to like parts throughout the several views of the

drawings. 60 The drawers 1, of which a number are shown in Fig. 1, are adapted to be received within openings in a case or compartment, the openings in the present construction being bounded by the ends 2 of the casing or 65 compartment, and partitions 3 interposed between the ends. The case or compartment is provided with the usual back 4 and horizontal members 5 may be used to provide bottoms for the drawer receiving openings 70 though it is to be understood that the particular construction of the case or compartment which receives the drawers is not an essential feature of the invention. The 75 fronts of the drawers are shown at 6 and it will be noted that at each end they slightly overlap the front edges of the ends 2 and partitions 3 in the casing so that if the drawer is not stopped when it is inserted in an opening these ends of the fronts 6 strike 80 against the front edges of ends 2 and partitions 3 tending to separate said fronts from the rest of the drawers.

Each partition 3 is slotted as shown at 7, the slot terminating at its rear end a distance in front of back 4. A sheet metal member comprising an upright section 8 from which are bent back parallel spaced apart arms 9 is placed in this slot. The section 8 has a width equal to the thickness of the partition 3 and the arms 9 are spaced apart a distance equal to the width of said partition so that the member may be located in the slot with the arms pressing against each side of the partition back of the slot while the 90 section 8 of said member lies closely against the partition. A downwardly projecting brad or tang 10 is formed integral with the member and is adapted to be driven into the partition as shown in dotted outline in Fig. 100 2, serving to hold the member firmly in position. The upper end of the section 8 is widened and turned forward making a head 11 to the section 8, the function of which

will later appear. After this sheet metal member has been secured in position a stirrup member is placed in position, this member consisting of spaced apart legs 12 connected at one end by a cross member 13, the free ends of the legs being turned outwardly in opposite directions as shown at 14. The distance between legs 12 is equal to the thickness of the partition 3, this being also the 10 width of the member 8. The width of the legs 12 is equal to the distance between the upper edge of a member 9 and the lower edge of the head 11 so that the stirrup member may be passed over the members 9 and 15 underneath the head 11, being guided and held in horizontal position by said parts 9 and 11. A screw 15 passes through the cross member 13 and bears at its end against the upright section 8, the screw being provided with a head 16 so that it may be easily turned.

With the members thus assembled and in place it will be noted that the parts 14 extend outwardly substantially at right angles to the partition 3 and are interposed in the path of movement of a drawer which moves along either side of the partition. When the rear end of the drawer strikes one of these parts 14 it is stopped against 25 further movement and all of the force of contact between the drawer and said members 14 is transmitted through the screw 15 against the section 8 of the sheet metal member which is backed against the partition 3. Accordingly it will be evident that 30 it is a practical impossibility to injure this stop in any manner. Furthermore by reason of the adjustable relation of the stirrup member to the relatively stationary member 35 that is shown in Fig. 4 the stops may be moved backward or forward and adjusted to the best position for the drawer so as to stop a drawer before its front 6 comes into contact with the front edges of ends 2 or 40 partitions 3 of the casing or compartment. 45

Various changes in detail of construction may be resorted to without departing from the invention which is defined in the appended claims. Accordingly I consider 50 myself entitled to all modifications of structure falling properly within the scope of said claims.

I claim:

1. In combination, a casing having ends and a slotted partition to divide the casing into adjoining drawer receiving openings, and a stop device located in the slot of said partition and adjustably and removably secured thereto, said stop device having oppositely extending parts extending into the path of movement of drawers inserted into said adjoining drawer openings.
2. In combination, a casing having a drawer receiving opening, one side of which

is bounded by a slotted member, a stirrup 65 member provided with spaced apart legs positioned in the slot and with a leg located at each side of the slotted member, an extension to a leg of the stirrup member projecting into the drawer opening and means 70 for adjusting the stirrup member with respect to the slotted member, substantially as described.

3. In combination, a casing having ends and a slotted partition between the ends to 75 divide the casing into adjoining drawer receiving openings, a U-shaped stirrup member located in the slot of the partition and with a leg thereof at each side of the partition, outwardly projecting extensions at the 80 ends of said legs, and means to adjust the stirrup member with respect to the partition.

4. In combination, a casing having ends and a slotted partition between the ends to 85 divide the casing into adjoining drawer receiving openings, a U-shaped stirrup member located horizontally in the slot of the partition with a leg thereof at each side of the partition, and an extension at the end 90 of each leg projecting into the drawer receiving openings.

5. In combination, a casing, a slotted partition therein to divide the casing into adjoining drawer receiving openings, a U- 95 shaped stirrup member located horizontally in the slot with a leg thereof at each side of the partition, an extension at each end of each leg projecting into the drawer receiving openings, means to adjust the stirrup member with respect to the partition, and means to hold said member in horizontal position, substantially as described.

6. In combination, a casing, a partition therein to divide the casing into adjoining drawer receiving openings, said partition being slotted horizontally for a portion of its length, the slot terminating a distance in front of the rear end of the partition, a U-shaped member located in the slot with 105 the legs thereof extending rearwardly one at each side of the partition, an adjusting screw passing through the cross member connecting the front ends of said legs, and an extension bent from the rear end of each 110 leg and projecting into the adjacent drawer receiving member.

7. In combination, a casing, a slotted partition therein to divide the casing into adjoining drawer receiving openings, said 115 partition being slotted horizontally for a portion of its length, the slot terminating a distance in front of the rear end of the partition, a member located in the rear portion of the slot and contacting against the partition, legs bent from said member extending rearwardly at each side of the partition, 120 a head to said member slightly wider than 125

the body of the member, a U-shaped member located horizontally in the slot having rearwardly extending legs located one at each side of the partition directly above the legs of the first member and below the head thereof, an extension bent at the end of each leg projecting into the adjacent drawer receiving opening, and a screw pass-

ing through the cross member connecting the front ends of the legs of the U-shaped member, the end of the screw engaging against the first member, substantially as described.

In testimony whereof I affix my signature.

CHARLES H. ANDERSON.
